UNITED STATES PATENT OFFICE.

JAMES E. POWERS, OF SALINA, KANSAS.

DESIGN FOR A WINDOW-SHELF BRACKET.

SPECIFICATION forming part of Design No. 33,781, dated December 25, 1900.

Application filed March 15, 1900. Serial No. 8,840. Term of patent 7 years.

To all whom it may concern:

Be it known that I, JAMES E. POWERS, a citizen of the United States of America, and a resident of Salina, county of Saline, State of Kansas, have invented and produced a new and original Design for a Window-Shelf Bracket, of which the following is a specification.

My invention relates to brackets designed to be attached to a window-casing for supporting a shelf in front of the window-shade.

In the accompanying drawings, Figure 1 is a perspective view, and Fig. 2 is a plan, of a bracket made according to my design.

In the said drawings, A represents the vertical, and B the horizontal, portions of an ordinary bracket. The portions A and B are connected together by scrollwork C, one part of which is given a lateral bulge, as shown at

D. The bulging portion D lies parallel with and adjacent to the vertical portion A and connects it to the other portions of the bracket, thus leaving an open vertical space opposite the front face of the said portion A.

The leading feature of my design consists of the vertical and horizontal portions A and B, connected together by a scrollwork having the lateral bulge D.

What I claim is—

The design for a window-shelf bracket as herein shown and described.

Signed by me at Salina, Kansas, this 7th day of March, 1900.

JAMES E. POWERS.
